UNITED STATES PATENT OFFICE.

GEORGE S. KNAPP, OF CHICAGO, ILLINOIS, ASSIGNOR TO KNAPP BROS
MANUFACTURING COMPANY, A CORPORATION OF ILLINOIS.

METAL CORNER-BEAD FOR THE PROTECTION OF PLASTERED CORNERS.

No. 844,812.

Specification of Letters Patent.

Patented Feb. 19, 1907.

Application filed March 21, 1906. Serial No. 307,248.

To all whom it may concern:

Be it known that I, GEORGE S. KNAPP, a citizen of the United States, residing in Chicago, in the county of Cook and State of Illinois, have invented certain new and useful Improvements in Metal Corner-Beads; and I do hereby declare the following to be a full, clear, and exact description of the invention, such as will enable those skilled in the art to 5
10 which it appertains to make and use the same.

My invention relates to improvements in metal corner-beads, and particularly to corner-beads made of one piece of sheet metal doubled back upon itself on a central longitudinal line.

One of the salient objects of my invention is to provide a cheap, efficient, and simple metal corner-bead structure of the class specified, easy of manufacture and which can 20
25 readily be attached to a relatively distant supporting structure or "construction" to afford a true plumb corner-surface irrespective of variation in the support or construction from a true vertical line.

Other and further objects of my invention will become apparent to those skilled in the art from the following description, taken in conjunction with the accompanying drawings, wherein—

Figure 1 is a perspective view of a corner-bead embodying my invention. Fig. 2 is a transverse section of my corner-bead applied in a wall structure, and Fig. 3 is a plan view of the blank before bending.

Throughout the drawings like numerals of reference refer always to like parts.

In the drawings, 5 indicates the head of the bead, preferably formed by bending the uninterrupted central portion of the blank 40
45 (shown in Fig. 3) upon itself into C shape, and 6 6 represent wings integral with and radiating from the head. These wings start from the head in such relation as to include therebetween an angle of less than ninety degrees and for a short distance from the head are preferably longitudinally continuous or uninterrupted.

To each of the wings 6 6 are integrally connected a number of long slender fingers 7 7, 50
55 forming lateral continuations of the wings and curving apart from an angle of less than ninety degrees at their bases to stand at an angle of substantially ninety degrees to each other at their extremities. The fingers 7 on

opposite sides are preferably paired or arranged in lateral alinement, and on each side the fingers are preferably spaced apart by distances approximately equaling the width of a blade, said fingers being by reason of their length and slenderness relatively springy at 55
60 their extremities. Nail-holes 8 8 are preferably provided in the free extremities of the fingers 7 to receive the attaching-nails 9.

In the formation of my improved corner-bead the structure is first blanked out of a sheet of metal in the form shown in Fig. 3 and thereafter bent up or folded longitudinally in the configuration shown in Fig. 1. It will be observed that since the fingers are 65
70 preferably spaced apart by distances equal to the width of the fingers a minimum waste in material in manufacture is incurred, and the parts cut out to form the spaces of fingers in one strip constitute the fingers of the next adjoining strip.

In the use of corner-beads as heretofore made difficulty is experienced in the fastening of the bead to the construction or supporting structure, owing to the fact that the studding or other construction-work is apt to be uneven, irregular, or out of plumb, and, further, it is often quite distant from the corner-line of the plastering. With many metal corner-beads commonly employed in practice the attaching structures are relatively 85
90 narrow, stiff, and arranged at a predetermined angle, usually ninety degrees, which necessitates their being applied in very close conformity to the corner of the studding or construction, so that the heads or noses of the beads are difficult to plumb, and for attachment to distant construction the use of attaching-wires or removable clips is necessitated, at increased expense and large expenditure of time. These difficulties my invention overcomes, as the long fingers are in practice attached to the studding or other construction by nails 9 at a considerable distance from the corner of the construction and from the head of the bead, so that comparatively wide variation from plumb in the edge of the construction will have no effect upon the bead, and, furthermore, exact adjustment of the bead as to location and plumb may readily be obtained in virtue of 95
100 the resilience of the bead and fingers and the resultant ease with which the bead in course of application responds to manipulation of

the party applying it. Also it will be observed the independent interspaced and relatively numerous fingers enable the facile attachment of the beading with firm secure bearing and anchorage irrespective of sharp irregularities in the surfaces of the construction without resort to any makeshifts of suspension attaching-wires, clips, or the like, and the increasing angular opening between the opposite fingers prepares the bead normally for attachment to the construction in proper relation to position the head at a distance from the construction easily variable to compensate for any desired thickness of plaster.

Having thus described my invention, what I claim, and desire to secure by Letters Patent of the United States, is—

1. A device of the character described, comprising in its structure a continuous longitudinal, folded head, and a series of long, slender, resilient fingers directly radiating from the head on opposite sides.
2. A device of the character described,

comprising in its structure a continuous longitudinal, C-shaped head, and a series of long, slender, resilient fingers, integral with the head and radiating therefrom on opposite sides at an angle of less than ninety degrees, said fingers being curved outwardly to approximately right-angle relation at their extremities.

3. A device of the character described, formed of a unitary sheet of sheet metal, cut to provide on opposite sides relatively long, slender fingers, extending outwardly from a central uninterrupted strip, said central strip being bent to provide a longitudinal, continuous, folded head, and wings radiating therefrom at an angle of less than ninety degrees to each other, the fingers being curved apart to approximately right angles to each other at their extremities.

GEORGE S. KNAPP.
